(57) **CLAIM**

The ornamental design for a kiln brick protective collar with apertures, as shown and described.

DESCRIPTION

FIG. 1 is a perspective view of a kiln brick protective collar with apertures showing my design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines in the drawings depict portions of the kiln brick protective collar with apertures that form no part of the claimed design.

1 Claim, 3 Drawing Sheets
